ATTORNEYS

UNITED STATES PATENT OFFICE.

WILLIAM H. CHENERY, OF MONTREAL, QUEBEC, CANADA.

DETACHABLE TREAD FOR FOOTWEAR.

Application filed February 4, 1924. Serial No. 690,573.

To all whom it may concern:

Be it known that I, WILLIAM H. CHENERY, a subject of the King of Great Britain, and resident of the city of Montreal, in the Province of Quebec, have invented certain new and useful Improvements in Detachable Treads for Footwear, of which the following is a full, clear, and exact description.

This invention relates to new and useful improvements in detachable treads for footwear or the like and the object of the invention is to provide a simple, inexpensive tread which will be easily attached to footwear and will automatically lock itself in position.

Another object is to provide a detachable tread for footwear which, when fixed to the footwear, will tend to hold itself securely in position through the action of walking.

A further object is to provide a spring grip between the detachable portion and the fixed portion of the heel or the like in the vertical direction, which will form a close joint between the contracting portions.

A still further object is to provide a detachable tread in which the spring locking mechanism will be protected from coming in contact with objects which may unlock same.

In my invention I provide a tread of leather, rubber or the like to which is attached a plate having hooks which are formed to provide a spring grip on the plate attached to the fixed portion of the footwear. The plates are attached to their respective portions of the device by means of rivets formed integral with plates. A spring automatic locking means is provided in the upper portion of the footwear, said means being adapted to engage with the hooks which pass through apertures formed in the upper plate. The upper plate is provided with an upwardly extending lug having an aperture formed therein, to provide easy access to the upwardly extending portion of the spring locking means. The lug also provides a protection against objects which may come in contact with the locking device and unlock same.

In the drawings:

Figure 1 is a side of the heel of a shoe, having my improved detachable tread.

Figure 2 is a plan looking on the underside of the fixed portion of the heel shown in Figure 1.

Figure 3 is a sectional elevation taken on the line 3—3 Figure 2. 55

Figure 4 is a plan view of the detachable tread.

Figure 5 is a sectional elevation taken on the line 5—5 Figure 4.

Figure 6 is a side elevation of one modification of the device applied to rubber heels. 60

Figure 7 is a plan view of the fixed portion of the heel.

Figure 8 is a sectional elevation taken on the line 8—8 Figure 7. 65

Figure 9 is a plan view of the detachable portion of the heel shown in Figure 6.

Figure 10 is a sectional elevation taken on the line 10—10 Figure 9.

Referring more particularly to the drawings, in which my device is applied to the heels of footwear for illustrative purposes only, 11 designates the upper of a shoe to which is securely attached the fixed portion 12 of the heel. The lower surface of the 75 portion is provided with a recess 13 equal in depth to the thickness of the plate 14 which may be attached to the portion 12 by means of the prongs 15 which are bent over to hold the plate in position as shown in 80 Figure 3. The plate fits into the recess having a small margin 16 around the outside edges of the heel. The prongs are punched from the plate and holes 17 may also be punched in the plate for attaching the heel 85 to the upper. Slots 18 are punched in the plate and the portion 12 may be provided with shallow recesses 19 adapted to coincide with slots 18 for a purpose hereinafter described. In the centre of the heel an aperture 20 is provided. Attached to the plate 14 is the spring locking device 21 which is provided with a downwardly projecting portion 22 adapted to coincide with the slot 20. This locking means is made from spring 90 steel or such like material and is attached to the plate 14 by any suitable means, while the other end is bent upwardly as indicated at 23 to form an operating means for the spring. To protect this end from coming 100 in contact with objects on the ground, part of the plate is bent upwardly as indicated at 24 and provided with a slot 25 through which the end of the thumb may be pushed to operate the locking device. The heel may 105 be provided with an elongated recess 26 to

allow free movement of the spring locking means. The detachable portion or tread 27 is recessed to receive a plate 28 and prongs 29 are punched therefrom to attach the plate 5 to the tread. Projecting upwardly from the plate are the hooks 30 which are punched from the plate, part of said hooks being adapted to lie horizontally with the plate. The ends of the hooks are curved to form a 10 grip on the plate 14 when the hooks are pushed through the apertures 18 and 20. The hooks are so positioned that when the surface 31 of the hooks engages with edges 32 of the slots 18 the outside edges of the 15 heel will coincide. When in this position, the spring locking means is adapted to engage the back 34 of one of the hooks thereby locking the tread in position until the spring is operated manually. The above description deals specifically with the device 20 as disclosed in Figures 1 to 5 inclusive.

In Figures 6 to 10 inclusive, I have shown one modification of the device which is particularly adapted for heels of rubber construction. 25 The general construction is something similar to that shown in Figures 1 to 5 except that the attaching means between the tread portion and its plate consists of hollow rivets 35 held in position in the tread portion, said rivets being adapted to be flanged over the apertures 36 formed in the plate. This takes the place of the prongs shown in Figure 5 as this prong construction is unsuitable for heels of rubber construction. No 30 prongs are provided in the plate shown in Figure 7 and designated 14^a. The plate 14^a is provided with apertures 37 through which, and the portion 12^a, screws may be placed for attaching the device to the upper. Also, on 35 this modified form the rubber is adapted to extend completely around the plates and the guard 24 so that when the tread is attached no portion of the attaching means is exposed.

40 The spring locking means shown in Figures 6 to 8 inclusive is provided with a downwardly projecting portion 22^a of rectangular formation, the back side 38 of which is adapted to frictionally engage with an upwardly projecting portion 39 of the plate 14^a formed by bending upwardly one of the sides of the plate surrounding the aperture 20. The front side 40 of the locking means is spaced from the edge 41 of the 45 aperture 20^a, a distance equal to the thickness of the hook 30 to allow the neck 42 of the hook to engage with the plates 14^a before the spring falls into the position behind the hook as shown in Figure 6. The projecting

portion 39 by frictionally engaging with the 60 side 38 assists in holding the spring in the locked position until unlocked by forcing the spring out of engagement with the hook.

It will be readily understood that with 65 very slight alteration in shape this device may be used for attaching sole treads to foot-wear.

In operation the heels are placed in position with the hooks entering the slots in the upper plate by pushing the lower portion in 70 the direction indicated by arrow "X". The hooks engage with the upper plate and said hooks being curved at their ends tend to draw the parts of the heel together. The hooks are placed facing the direction of the 75 arrow so that pressure exerted on the back of the heel always tends to keep the tread in position. When the tread is placed in the position shown in Figure 1, it is automatically locked by the action of the spring, part 80 of which engages with the back of one of the hooks to hold the device in position. The upper plate is also provided with a guard which prevents objects from coming in contact with the spring to unlock same during 85 walking. As will be seen from the foregoing description heels made in this manner will be very easily and inexpensively manufactured and when repairs are required these 90 may be done expeditiously and neatly by the wearer.

Having thus described my invention, what I claim is:—

A heel structure comprising an upper part having a metal plate secured to its bottom surface, said part and plate being formed with registering openings and one edge of said plate being turned upwardly to provide a guard flange, a lower part having a metal plate secured to its upper surface, a plurality of hooks projected upwardly from said last mentioned plate and adapted to be inserted in the openings of the first mentioned plate and to grip the latter when shifted laterally thereon subsequent to insertion through said openings, and a spring locking strip having one end secured on the first mentioned plate and provided with an intermediate projection adapted to engage in one of the openings in said plate and behind the hook inserted in said opening, the free end of the locking strip being bent upwardly to lie against the inner surface of the guard flange and being accessible through an opening formed in the latter.

In witness whereof, I have hereunto set 115 my hand.

WILLIAM H. CHENERY.
